UNITED STATES PATENT OFFICE.

WILLIAM WALTER OWEN, OF OAK PARK, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed June 12, 1918, Serial No. 239,504. Renewed July 19, 1924.

To all whom it may concern:

Be it known that I, WILLIAM WALTER OWEN, a citizen of the United States of America, and a resident of Oak Park, in the county of Cook and State of Illinois, have invented certain new and useful Improvements in Automatic Telephone Systems, of which the following is a specification.

My invention relates in general to that type of telephone system in which connections are established between two subscribers automatically by the use of so called automatic switches without requiring the intervention of an operator.

More specifically my invention relates to certain improved switches of large capacity and methods of operating the same whereby the capacity of an automatic system may be greatly increased and at the same time the operations required of a subscriber are reduced to a minimum.

Among the objects of my invention is to provide in standard type of Strowger switches such means as to enable said switches to have a much greater capacity so that the number of switches may be greatly reduced, thereby cutting down the initial cost of installation and whereby these large capacity switches may be controlled without requiring the subscriber to operate his calling device as many times as in the past to send the digits of a called number and without requiring any material change in the mechanism of the automatic switches or of the calling device.

My invention is especially valuable in a private branch exchange of large capacity or in a large exchange of any other type. For instance, if it were desired to install an exchange of a million lines or thereabouts the subscribers' directory numbers, in systems such as have been installed in the past, would have so many digits or figures as to be a very serious drawback from the subscriber's view point, and such an exchange would be quite costly in view of the large number of switches required. In a system of the type which I have illustrated in the drawings, however, it will be seen that a subscriber might call any other subscriber in a 27000 line system with only three digits, in a 810,000 line system with only four digits, and so on, said digits also being a

mixture of letters and figures which are much easier to remember than an all figure number.

In Fig. 1 of the drawings I have shown a layout or trunking diagram of a system embodying my invention, showing only a portion of a 27000 line system and the routes taken by calls from the various subscribers.

Figures 2 and 3 show the switches used in such a system when a connection is extended from a calling subscriber A (Figure 2) through a line switch C, a selector switch E, and a 900 line connector switch H (Fig. 3). I have shown all the apparatus in its normal position in these drawings. Fig. 4 shows the preferred form of calling device to be used in my system. The calling device is of the well known type which sends from one to ten impulses to the switches, depending upon the hole used to rotate the dial. The only difference between this and the standard ten impulse calling device is that the dial instead of having only one set of finger holes, has three such sets, each having the same relation to the operating or impulse sending mechanism; that is, if 1, A or L are used only one impulse will be sent to the central exchange on the return movement of the dial, while if 3, C or N are used to operate the device only three impulses will be sent in either case on the return movement. If however, any of the letters A to K are used to control the device then the springs 2 and 3 will be operated once for any digit A—K to ground one side of the line circuit to in turn pull up a differential relay at the exchange. If any digit L to X is dialed then the springs 4 and 5 will be operated once to remove the short circuit from a high resistance 6 at the substation. These springs 2, 3, 4 and 5 it will be understood, may be mounted in any way or operated in any manner as long as they close contact once on the forward movement of the dial before the regular digit is sent out by the return of the dial.

The marginal and differential relays controlled by these two pairs of springs are associated with each switch which is used and are operated to pick out a desired set of line and private wipers in a large capacity switch which carries a plurality of such sets simul-

aneously to like points in banks associated with each wiper.

I have shown in the drawings only a line switch, a first selector, and a connector, although it will readily be seen that the first selector may be omitted or more selectors may be added without in any way departing from the spirit of my invention.

In the diagram in Fig. 1 I have shown a portion of a 27,000 line system illustrating an application of the principles of my invention. I have shown the first three 900 line groups of the first 9000 group across the upper part of the figure and the first three 900 line groups of the second 9000 group across the lower part of the figure. It will be understood that in such a system there will be arbitrarily three groups of 9000 lines each, 10 groups of 900 lines each in each 9000 line group, and 6 groups of 150 lines each in each 900 line group. Each first selector has access to 300 trunks, the first 100 or the lower bank of each selector leading to connectors in each 900 group of the first 9000; that is the first level of the first selector E leads to the ten connectors H in the first 900 of the first 9000; the second level to ten connectors in the second 900 of the same 9000 and so on. The second bank of this selector E leads to ten connectors in each of the ten 900 groups of the second 9000, and the third bank leads to ten connectors in each 900 group of the third 9000. In the same manner a subscriber D for instance, in the second 900 of the second 9000 would also have access through the selectors F with ten connectors H' in each 900 groups of the first 9000, through the first bank of any selector F; with ten connectors H² in each 900 group of the second 9000 through the second bank, and also with ten connectors in each 900 group of the 3rd 9000 through the third bank. Each connector has access to 900 lines and for the purpose of illustration I have shown 60 connectors as having their individual contacts multiplied and leading to the 900 subscribers of one sub-group. The percentage may be varied according to traffic conditions.

I will now point out in detail the operation of my system when a subscriber such as A desires to call any other subscriber, reference being had to the accompanying drawings.

When the subscriber at substation A (Fig. 1) removes his receiver a circuit is closed for the line relay 7 of the rotary line switch C (Fig. 2). Relay 7 energizes to close a series circuit for relay 8 and magnet 9, and also closes a circuit from private wiper 12 direct to rotary magnet 9. The switch now rotates as this circuit meets grounded contacts of busy trunk lines to operate the magnet 9 and as soon as an idle trunk is reached, relay 8 being no longer

short circuited by ground on wiper 12 energizes in series with magnet 9 to disconnect the line of substation A from the line relay 7 and connect said line to the line relay 13 of selector E through wipers 10 and 11.

The circuit for line relay 13 extends from ground through the lower winding of relay 13, lower winding of the differential relay 15, wiper 11, to and through substation A, wiper 10, upper winding of relay 15, marginal relay 14, and upper winding of relay 13 to battery. Relay 15 does not energize over this circuit as the currents in its two windings oppose each other. Relays 13 and 14, however, energize and attract their armatures. Relay 13, upon energizing, closes a circuit for slow relay 16 and opens one point in the circuit of release magnet 17. Relay 14 upon energizing, has no effect at this time except that it opens one point in the circuit of switching relay 18. Relay 16 supplies a holding ground to the relay 8 of line switch C, and prepares a circuit for the vertical magnet 20 and slow relay 21.

The subscriber at A may now operate his calling device to send the first digit of the called number. This digit may be any one of 30 characters, that is, it may be any figure from 1-0, any letter A-K or any letter L-W. If any figure (1-0) is dialed then neither of the relays 14 or 15 will have any function and the line relay 13 will be operated in accordance with the number dialed (1 for instance) to step the wipers 22-30 inclusive, to the first level of their respective banks. As neither of the relays 14 or 15 have closed their respective circuits, and therefore relays 18 and 19 are not energized, then the trunk line and the test conductor will be connected only to the wipers 22, 23 and 24, respectively, the other wipers being open at the contacts of relays 18 and 19.

It will be noticed that although relay 14 will deenergize at each impulse with the line relay, the circuit of the switching relay 18 will not be closed as the said circuit extends from ground through springs 31, springs 32 and 33, off normal springs 34, springs 35, and said relay, so that, in order to close said circuit, relay 14 must be deenergized while the line relay is energized. If any letter A-K is used for the first digit, then, as the calling device is drawn down on the forward movement and the springs 2 and 3 are closed, a ground will be supplied to the line circuit which short circuits one winding of each relay 13 and 15. Relay 13 is not affected by this operation but relay 15 now attracts its armature to close springs 36 and energize the switching relay 19. Relay 19, upon energizing, locks itself energized to the ground on relay 16, and connects the extended trunk circuit to the wipers 25 and 26 and the test wiper 27. If the first digit should be any of the letters L to W then the springs 4 and 5

associated with this outer row of holes will be operated momentarily to include the resistance 6 in the line circuit. This operation does not affect the relays 13 or 15 but causes the marginal relay 14 to fall back to close the previously traced circuit of the relay 18. Relay 18 will therefore energize and in this case switch the trunk to the upper set of wipers 28, 29 and 30, and lock itself to ground. As soon as the preliminary switching of wipers is completed and as the dial returns, the springs CD at the substation are interrupted in the usual manner to step all of the wipers to some level of their banks. Assuming that subscriber A desires to call a subscriber A' for instance, in the first 9000 group, then the first digit would be a figure and neither of the relays 18 or 19 would be operated. The vertical magnet 20 operates to step the wipers to the desired level and as soon as the impulses for this digit cease, relay 21 falls back to close a circuit for rotary magnet 37 from ground through springs 38, springs 39 and 40, springs 41, and magnet 37 to battery. Relay 42 was energized upon the initial energization of relay 21. As the test conductor is connected only to wiper 24 which is one of the lower sets of wipers, then the switch in rotating will select an idle trunk line in its lower bank. As soon as an idle trunk is found the relay 43, which has heretofore been shorted in passing over busy trunks, energizes to disconnect the magnets of switch E from the trunk circuit to extend the same to the line wipers 22 and 23 which are now resting upon an idle trunk line leading to an idle connector such as H (Figs. 1 and 3). This connector is one of the ten which is accessible to subscribers of the first 150 of each 900 and which has access to 900 lines in the first 9000 line group. The connector H is of the well known Strowger type of switch, being side switchless and having, instead of the usual pair of line and private wipers, nine sets of line and private wipers, each being adapted to connect with any one of 100 lines. The subscriber must therefore select one of the nine wipers to determine in which 900 his called line is located and must then step the switch up and around to the desired contacts. All the wipers will of course move together but only those wipers will be effective which are selected by the combination of letters or figures used in operating the calling device. As the first digit was described as 1 the selector has elected the first 900 group of the first 9000 and the connector H therefore must now be operated to pick out the first set of line and private contacts in the first level of the lower bank of said connector. As in the case of the selector, the circuit for the line relay 45 includes also a marginal relay 46, and a differential relay 47 which relays are controlled in the same manner as the relays 14 and 15 of selector E. The first digit being 1 (in this case) relays 46 and 47 have no effect and the trunk circuit through the connector remains connected to the wipers which have access to the first 100 lines in the 900. As the impulse for this digit is delivered to line relay 45, said relay falls back to close a circuit from ground through springs 48, springs 49, relay 77, and vertical magnet 78 to battery. Magnet 78 therefore operates in the manner usual to switches of this type to step all the wipers 50-76 inclusive, to the first level of their associated banks. Relay 77, upon energizing, closes the springs 79 and 80 so that after the switch takes its first step and the off normal springs close, the circuit of the vertical magnet passes from springs 49 through springs 81, and through springs 80 and 79 to said relay magnet. After the impulse or impulses of this first digit cease, relay 77 falls back and prepares a circuit for the relay 82 and rotary magnet 83 at springs 80 and 84. The next digit being 1 the line relay falls back to operate relay 82 and magnet 83 in the usual manner. Magnet 83 steps the wipers to the first contact in the selected level and relay 82 connects the test relay 85 to the private wiper 52. Relay 82 is slow to fall back so that if the called line is busy and a ground present on the private contact thereof then relay 85 will energize and lock itself to ground at springs of slow relay 86 before relay 82 falls back. Relay 85 connects busy tone to the line circuit, and opens a point in the circuit of relay 82 and magnet 83, whereupon the calling subscriber may release the connection and call again. If the called line is idle, however, relay 85 does not energize and as soon as relay 82 falls back a circuit is closed for the upper winding of wiper cut on relay 87 which extends from ground at springs of relay 86 through springs 88, upper winding of relay 87, springs 89, back contacts of relays 90, 91, 92 and 93, private wiper 52, and through the bridge cut off relay of the called line to battery. Relay 87 energizes to cut the line circuit of the called line through the springs 94 and 95, to the ringing circuit R and to the usual ring cut off relay 96. As soon as the called subscriber answers the relay 96 operates to disconnect the ringing circuit from the called line and connect said line to the substation A and to the windings of the back bridge relay 97 which supplies said called line with talking current. Conversation may now proceed in the usual manner and the connection will be released by the calling subscriber in the usual manner. Now should the subscriber have desired to call a subscriber whose line is located in the second hundred of this 900 group then he will call 1-1-A instead of 111. In this call the switches will be operated in

the manner explained until the last digit, when A is dialled after the switch has been operated vertically the relay 47 will be operated by the closure of springs 2 and 3.

5 The energizing of relay 47 will now close a circuit for the switching relay 93 from ground through springs 98, off normal springs 99 and 100, and relay 93 to battery. Relay 93 locks itself to ground at springs 10 of relay 86 and switches the trunk circuit from the wipers 50, 51 and 52 to the wipers 53, 54 and 55 which have access to the second hundred or second bank.

Should the desired subscriber's line be 15 located in the third hundred then the called number would be 1—1—L, that is, just before the last digit, the relay 92 would be operated by the springs 4 and 5 through the medium of marginal relay 46 and springs 20 102, 104 and 103 to switch the trunk circuit to the wipers 53, 54 and 55 which have access to said third hundred.

Should the called line be in the fourth hundred the called number would be 25 1—A—1. In this case just before the second digit the springs 2 and 3 would be operated to energize relay 47, and relay 47 closes a circuit for switching relay 91 through springs 98, 99 and 101, so that the trunk 30 is switched to wipers 59, 60 and 61. If the call line is in the fifth hundred then the called number would be 1—A—A. In this case springs 2 and 3 will be closed just before the second digit to operate relay 35 91 through springs 98, 99, and 101, and said springs will again be operated just before the last digit to cause relay 47 to close the circuit of relay 93, through springs 98, 99 and 100. The trunk circuit will be switched 40 in this case to wipers 62, 63 and 64 through front contacts 106 and 107 of relay 91 and through front contacts 107' and 108 of relay 93. Should the called line be in the sixth hundred the called number would be 45 1—A—L. In this case springs 2 and 3 will operate relay 47 before the second digit to energize relay 91 through springs 98, 99 and 101, and the springs 4 and 5 will operate relay 46 just before the last digit to energize 50 relay 92 through springs 102, 104 and 103. The trunk circuit will therefore be connected through front contacts 106 and 107 of relay 91 and through front contacts 109 and 110 of relay 92 to wipers 65, 66, and 67.

55 Should the called line be in the seventh hundred then the called number would be 1—L—1 and in this case springs 4 and 5 will be closed just before the second digit to cause relay 46 to energize relay 90 through 60 springs 102, 104, and 105, to connect the trunk through front contacts 111 and 112 of relay 90 to wipers 68, 69 and 70.

Should the called line be in the eighth hundred, then the called number will be 65 1—L—A and in this case springs 4 and 5

will be closed before the second digit to cause relay 46 to energize relay 90 through springs 102, 104, and 105, and springs 2 and 3 will be closed just before the last digit to cause relay 47 to energize relay 93 through springs 98, 99 and 100, thus connecting the trunk through front contacts 111 and 112 of relays 90 and front contacts 113 and 114 of relay 93 to wipers 71, 72 and 73.

Should the called line be located in the ninth hundred then the called number would be 1—L—L, and in this case the springs 4 and 5 would be closed before the second digit to cause relay 46 to energize relay 90 through springs 102, 104 and 105 and again just before the last digit to cause relay 46 to energize relay 92 through springs 102, 104 and 103, thus connecting the trunk circuit through front contacts 111 and 112 of relay 90 and front contacts 115 and 116 of relay 92 to the upper set of wipers 74, 75 and 76.

Thus it will be seen that the order of letters and figures in the called number determines the group of the called line, while the particular letter or figure used determines the line in the group.

It will be understood that in any of the above cases, although I have stated for instance, that to call into the 6th group the digit would be 1—A—L, yet it will be understood that there are 100 combinations which will select the same sixth set of wipers, that is 1—A—M to W, 1—A to B—M, and up to O—K—W, depending upon the location of the called line in that group, and also in the first group the number may be 111, 112, 113, 121, 122, etc.

All of the calls which I have so far described are in the first 9000 lines, and any line may make such a call by using any connector H, H', etc., of the first 9000. Now should the calling subscriber desire to call a subscriber in the second 9000, then the first digit will always be one of the letters A to K, and in this case the selector E will be operated as explained, that is, whenever the first digit of a number is any of the letters A to K, inclusive, the springs 2 and 3 at the calling device will be operated to cause

relay 15 of the selector to energize the switching relay 19 which in turn connects the line circuit to the line wipers 25 and 26 and the test conductor to the private wiper 27 instead of to wiper 24. In this case of course, the switch after selecting a level in the second 1000 group or in the second bank of the selector will rotate to automatically select an idle trunk line in the said level or an idle one of ten connectors which have access to a certain 900 group in said second thousand. In the same manner if the called number is located in the third thousand then the first digit of the called number will always be one of the letters L to W, inclusive, and in this case springs 4 and 5

and 5 will be closed before the first digit is sent out to cause relay 14 to energize the switching relay 18, which in turn switches the wipers 28, 29 and 30 into connection with the line circuit and a trunk leading to 10 connectors in the third 9000 will be selected.

It will therefore be seen that the system is divided first into three large groups of 9000 lines, which may be designated as the 10 1, A and L groups, and that each 9000 group is divided into ten sub-groups of 900 lines each, the particular 900 group in the selected 15 9000 group depending upon which one of the numbers or figures in a series are used; the 900 groups are further divided into sub-groups of 100 lines each, and the sub-group selected depends upon the order in which the 20 zones or rows on the calling device are used for the last two digits. This selection and distribution it is thought is new and constitutes a very great advance in the art as 25 it practically enables a subscriber to send five digits of a called number or more, with only three operations of the calling device and reduces the number of switches materially.

Having fully described and ascertained the features of my invention what I consider to be new and desire to have protected by Letters Patent will be pointed out in the appended claims.

What I claim is:

1. In a telephone system, an automatic switch, a plurality of sets of wipers for said switch, a second plurality of sets of wipers for the switch, a calling device for controlling said switch to extend a connection over any of said sets of wipers in accordance with two of the digits of a called number, means controlled by said calling device for automatically selecting one set of said first plurality of sets of wipers before the switch is operated in response to one digit, and means for automatically selecting one of said second plurality of sets of wipers before the switch is operated in response to another digit.

2. In a telephone system, an automatic switch, a plurality of sets of wipers for said switch, a calling device for controlling said switch to extend a connection over any of said sets of wipers in accordance with two of the digits of a called number, means controlled by said calling device for automatically selecting one of a pair of said sets of wipers before the switch is operated in response to one digit, means for automatically selecting one of another pair of said sets of wipers before the switch is operated in response to another digit, and automatic means controlled both before and after the switch is operated in response to the first digit for automatically selecting another set of wipers.

3. In a telephone system, an automatic

switch, a plurality of wipers for said switch, a calling device for controlling said switch to extend a connection over any of said wipers in accordance with two of the digits of a called number, means controlled by said calling device for automatically selecting one of a pair of said wipers before the switch is operated in response to one digit, means for automatically selecting one of another pair of said wipers before the switch is operated in response to another digit, and automatic means controlled both before and after the switch is operated in response to the first digit for automatically selecting one of a third pair of wipers. 80

4. In a telephone system, an automatic switch, a plurality of wipers for said switch, a calling device, a plurality of rows of finger holes for controlling said calling device to operate said switch, means associated with one of said rows of finger holes for causing said switch to extend a connection over one of said wipers, means associated with another of said rows of finger holes for causing said switch to extend a connection over a different one of said wipers, the wiper depending upon the row used, said means also for extending connections over others of said wipers when the calling device is controlled through the medium of more than one of said rows to operate the switch. 90

5. In a telephone system, an automatic switch, a plurality of wipers for said switch, a calling device, a plurality of rows of finger holes for controlling said calling device to operate said switch, means associated with one of said rows of finger holes for causing said switch to extend a connection over one of said wipers, means associated with another of said rows of finger holes for causing said switch to extend a connection over a different one of said wipers, the wiper depending upon the row used, and means for extending connections over others of said wipers when the calling device is controlled through the medium of more than one of said rows to operate the switch, the wiper used in the latter case depending upon the order in which the rows of holes were used to operate the dial. 110

6. In a telephone system, an automatic switch, a line leading to said switch, a plurality of wipers for said switch, a plurality of relays for said switch, a calling device for controlling said switch to extend connections, automatically controlled means in said switch for energizing only one of said relays before the switch is operated, or for energizing either of two other of said relays after the switch is partially operated, means controlled by each relay for connecting said line to a different one of said wipers, and means controlled by the energization of two of said relays for con- 125

necting said line to different ones of said wipers.

1. In a telephone system, a subscriber's line, an automatic switch accessible to said line, a calling device for said line for operating said switch first in a vertical direction and then in a rotary direction, a plurality of wipers for said switch, a plurality of relays for said switch, means controlled by the calling device for operating one of said relays before the switch is operated vertically to switch said line to one of said wipers, and means for operating another of said relays after the vertical movement of the switch to switch the line to another of said wipers.

2. In a telephone system, a subscriber's line, an automatic switch accessible to said line, a calling device for said line for operating said switch first in a vertical direction and then in a rotary direction, a plurality of wipers for said switch, a plurality of relays for said switch, means controlled by the calling device for operating one of said relays before the switch is operated vertically to switch said line to one of said wipers, means for operating said relay after the vertical movement of the switch to switch the line to another of said wipers, said means also for operating one relay before the vertical movement of the switch and another relay after the vertical movement of the switch to connect the line to another of said wipers.

3. In a telephone system, a subscriber's line, an automatic switch for said line, means on the line for operating said switch in a vertical and then in a rotary direction, a plurality of wipers for the switch, a plurality of relays for the switch, means for operating one of said relays before the vertical movement of the switch to connect the line to one of said wipers, and means for operating another of said relays after the vertical motion to connect the line to another of said wipers.

4. In a telephone system, a subscriber's line, an automatic switch for said line, means on the line for operating said switch in a vertical and then in a rotary direction, a plurality of wipers for the switch, a plurality of relays for the switch, means for operating one of said relays before the vertical movement of the switch to connect the line to one of said wipers, said means for operating said one relay after the vertical motion to connect the line to another of said wipers, and means for operating another of said relays to switch the line to another of said wipers.

5. In a telephone system, a subscriber's line, an automatic switch for said line, means on the line for operating said switch in a vertical and then in a rotary direction, a plurality of wipers for the switch, a plurality of relays for the switch means for op-

erating one of said relays before the vertical movement of the switch to connect the line to one of said wipers, said means for operating said one relay after the vertical motion to connect the line to another of said wipers, 70 means for operating another of said relays before the vertical movement of the switch to connect the line to another wiper, and for operating said relay after the vertical movement of the switch to connect the line to another wiper.

6. In a telephone system, a subscriber's line, an automatic switch for said line, means on the line for operating the switch in a vertical and then in a rotary direction, a 80 plurality of wipers for the switch, a pair of relays for the switch, means for operating either of said relays either before or after the vertical operation of the switch, and means controlled by either relay for connecting the line to a different one of said wipers depending upon the relay energized and whether it is energized before or after the vertical movement of the switch.

7. In a telephone system, a subscriber's line, an automatic switch for said line, means on the line for operating the switch in a vertical and then in a rotary direction, a plurality of wipers for the switch, a pair of relays for the switch, means for operating 95 either of said relays either before or after the vertical operation of the switch, means controlled by either relay for connecting the line to a different one of said wipers depending upon the relay energized and whether it is energized before or after the vertical movement of the switch, and means controlled by said relays for switching the line to others of said wipers when either relay is energized both before and after the vertical 100 movement.

8. In a telephone system, a subscriber's line, an automatic switch for said line, means on the line for operating the switch in a vertical and then in a rotary direction, a 110 plurality of wipers for the switch, a pair of relays for the switch, means for operating either of said relays either before or after the vertical operation of the switch, means controlled by either relay for connecting the line to a different one of said wipers depending upon the relay energized and whether it is energized before or after the vertical movement of the switch, and means controlled by said relays for switching the line 115 to others of said wipers when either relay is energized both before and after the vertical movement, the wiper selected depending upon the order in which said relays are energized.

9. In a telephone system, a subscriber's line, an automatic switch for said line, a plurality of wipers for said switch, means on the line for moving said wipers in a vertical and then in a rotary direction, automatic 130

- means for grounding said line before the vertical movement of the switch to connect the line to one of said wipers, and for including a resistance in the line after the 5 vertical movement to connect the line to another of said wipers.
16. In a telephone system, a subscriber's line, an automatic switch for said line, a plurality of wipers for said switch, means on the line for moving said wipers in a vertical and then in a rotary direction, automatic means for grounding said line before the vertical movement of the switch to connect the line to one of said wipers, and for 10 including a resistance in said line to connect the line to another wiper.
- 15 17. In a telephone system, a subscriber's line, an automatic switch for said line, a plurality of wipers for said switch, means on the line for moving said wipers in a vertical and then in a rotary direction, automatically controlled by said first 25 means for grounding said line either before or after the vertical movement or for including a resistance in said line either before or after the vertical movement, and means for switching the line to a certain one of said wipers dependent upon the time the line is so controlled.
- 30 18. In a telephone system, a subscriber's line, an automatic switch for said line, a plurality of wipers for the switch, means on the line for operating the switch to move said wipers in a vertical and then in a rotary direction, means for grounding the line before the vertical movement of the switch 40 to connect the line to one of said wipers, or for grounding the line after the vertical movement to switch to a second of said wipers, means for including a resistance in the line before the vertical movement to 45 connect the line to a third wiper, or for including said resistance after the vertical movement to connect the line to a fourth wiper.
- 50 19. In a telephone system, a subscriber's line, an automatic switch for said line, a plurality of wipers for the switch, means on the line for operating the switch to move said wipers in a vertical and then in a rotary direction, means for grounding the line before the vertical movement of the switch 55 to connect the line to one of said wipers, or for grounding the line after the vertical movement to switch a second of said wipers, means for including a resistance in the line before the vertical movement to 60 connect the line to a third wiper, or for including said resistance after the vertical movement to connect the line to a fourth wiper, and means for switching the line to others of said wipers by grounding the line 65 both before and after the vertical movement or including the resistance both before and after.
20. In a telephone system, a subscriber's line, an automatic switch for said line, a plurality of wipers for the switch, means on the line for operating the switch to move said wipers in a vertical and then in a rotary direction, means for grounding the line before the vertical movement of the switch 70 to connect the line to one of said wipers, or for grounding the line after the vertical movement to switch to a second of said wipers, means for including a resistance in the line before the vertical movement to connect the line to a third wiper or for including said resistance after the vertical movement to connect the line to a fourth wiper, and means for switching the line to others 75 of said wipers by grounding the line both 80 before and after the vertical movement or including the resistance both before and after, or by grounding the line before the vertical movement and including the resistance after said movement.
- 90 21. In a telephone trunking system, lines divided into groups and sub-groups, said sub-groups being further divided into smaller groups, a calling device for each line having three rows of finger holes for controlling the same, means controlled by the operation of the device for the first digit of a called number for selecting one of a plurality of main groups, a sub-group in the main group and an idle trunk leading to that sub-group, means controlled by the operation of the device for the second and third digits of a called number for selecting a second sub-group in the selected 95 sub-group, a sub-group in the second selected sub-group, and a line in the third selected sub-group.
- 100 22. In a telephone trunking system, lines divided into groups and sub-groups, said sub-groups being further divided into smaller groups, a calling device for each line having three rows of finger holes for controlling the same, means controlled by the operation of the device for the first digit of a called number for selecting one of a plurality of main groups, a sub-group in the main group and an idle trunk leading to that sub-group, means controlled by the operation of the device for the second and third digits of a called number for selecting a second sub-group in the selected 105 sub-group, a sub-group in the second selected sub-group, and a line in the third selected sub-group.
- 110 23. In a telephone system, a calling line, a switch for said line having a plurality of 115 groups and lines selected depending upon the row of finger holes used for sending each digit and the order in which the various rows of holes were used.
- 120 24. In a telephone system, a calling line, a switch for said line having a plurality of 125 groups and lines selected depending upon the row of finger holes used for sending each digit and the order in which the various rows of holes were used.
- 130 25. In a telephone system, a calling line, a switch for said line having a plurality of 135 groups and lines selected depending upon the row of finger holes used for sending each digit and the order in which the various rows of holes were used.

wipers, lines accessible to each wiper, means for operating said switch in response to two digits of a called number to extend a connection over one of said wipers to a called 5 one of said lines, a plurality of relays for switching the calling line into connection with any of said wipers, any of said relays operable automatically either before the first of said digits or after the first one of 10 said digits.

24. In a telephone system, a calling line, a switch for said line having a plurality of groups of lines accessible thereto, wipers for the switch, means operated in response 15 to impulses corresponding to digits of a called number for moving said wipers to extend a connection, and automatic means operated independent of any movement of the wipers for determining the group of 20 lines into which the call is to be extended,

said group selecting mechanism consisting of a pair of relays each operable either before or after the first of said digits.

25. In a telephone system, an automatic switch, a line leading to said switch, a plurality of wipers for said switch, a plurality of relays for said switch, a calling device for controlling said switch to extend connections, automatic means in the switch for energizing one of said relays after the 25 switch is seized or for energizing certain pairs of said relays, each relay having means for connecting the line to a different one of said wipers, and means controlled by the energization of any pair for connecting the line to a different one of said 30 wipers.

Signed by me at Chicago, Cook County, Illinois, this 4th day of June, 1918.

WILLIAM WALTER OWEN.
